TRAIN HEATING SYSTEM AND TRAP
THEREFOR

Ernest J. Drewyour, Detroit, Mich.

Application November 14, 1932, Serial No. 642,558

3 Claims. (Cl. 236—56)

My invention relates to train heating systems. The ordinary train heating system includes a train line running from the locomotive beneath each car of the train to its rear end. In each 5 car, a branch runs from the train line to a heating coil within the car and each such coil has a discharge end controlled by a thermostatically operated valve for discharging condensate formed therein. However, there is quite a little 10 condensate formed in the train line itself, particularly in the coupling sections between cars and at times of low temperatures, especially if the wind is in such direction as to increase the draft against the couplings. Unfortunately, the 15 condensate from the couplings in other parts of the train line cannot pass out thru the traps associated with the car heating coils because such coils are above the level of the train line. The train line condensate, is therefore carried 20 throughout the whole length of the train and discharged at the rear end of the last car of the train. Such condensate is often sufficient to fill a large proportion of the free cross-section of the train line so that the train line becomes 25 largely choked against passage of steam and the pressure and temperature in the rear portion of the steam line are greatly lowered so that it is difficult to keep the rear cars of the train sufficiently heated.

30 It has been proposed to trap out the condensate from the train line at various points in its length and such drawing off the condensate would undoubtedly improve the efficiency of the system. However, there are no traps on the 35 market well adapted for use under the conditions of such systems.

The ordinary float trap is impractical for use in the train lines of train heating systems because, enroute as well as when making up a 40 train, the traps at different points in the train are subjected to widely varying pressures. It is well known that float traps are designed for certain pressures and do not operate satisfactorily at pressures greatly different from the ones for 45 which they are intended. In a train line, the pressure may vary from 180 to 200 pounds gage near the locomotive to practically zero gage pressure at the end removed from the locomotive. Float operated traps also are subject to 50 freezing when no steam is available.

Aside from the float trap, the only one in ordinary use is the thermostatically operated trap. Such thermostatic traps are impractical for use 55 in train lines of train heating systems, because the temperature of the steam necessarily varies with the pressure and, as mentioned above, the pressures may vary along the train from 200 pounds gage to zero gage. It would be necessary, 60 therefore, if thermostatic traps were used to ad-

just them continuously enroute, which is impossible.

It is an object of my invention to provide an arrangement whereby the said difficulties may be eliminated or at least minimized.

In order that my invention and its objects and advantages may be fully and readily understood, I will now describe in detail and in connection with the accompanying drawing a train heating system and trap therefor, selected by 10 way of example from a number of possible embodiments of my invention. In the drawing,

Fig. 1 is a diagrammatic view of a portion of a passenger train having my invention applied thereto.

Fig. 2 is an elevation of a trap appearing in Fig. 1.

Fig. 3 is a fragmentary sectional detail of a portion of Fig. 2 illustrating on an enlarged scale a circuit controlling thermometer used in 20 my invention.

Fig. 4 is a sectional detail of an outlet valve whose casing appears in Fig. 2.

Fig. 5 is an elevational view partly in section of a switch box shown in Fig. 2 with cover removed.

Fig. 6 is a sectional detail on the line 6—6 of Fig. 5.

In the drawing, the train illustrated in Fig. 1 includes a locomotive having a boiler 10 connected to a passenger train, one of the cars of which appears at 12. A steam line 14 for heating cars 12 extends from the boiler 10 rearwardly beneath the tender 16 and passenger cars 12 to the last car of the train. Each car has one or more coils such as 18 connected to the steam line for heating the car when desired. Each car has thereon also one or more traps, one of which is illustrated at 20 and which serves also as a connecting point for the heating coils 18. However, I do not limit myself to the number of traps per car, to the location of traps 20 or to associating the traps on each car 12 with the heating coils.

Trap 20 is connected to line 14 at the points 22, 22 so steam may flow therethru in the desired direction as indicated by the arrows 23, 23.

The coils 18 are shown as connected to the top of the casing of trap 20 by pipe 24. A pipe 26 is provided for discharging water from the casing of trap 20 and shown as connected to the lower portion of such casing. A valve for controlling the out-flow thru pipe 26 is shown as having a body 28 close to the casing of the traps, the valve 30 within body 28 being shown as of the double seat type. However, I do not limit myself to any particular type of valve for controlling the out-flow from the trap. As shown, the stem 32 of valve 30 has a means associated therewith tending to open the valve. As shown, such means comprises a spring 34 having one end arranged to 55

push against a normally fixed gland 36 and the other against a collar 38 on the valve stem. However, I do not limit myself to spring means for this purpose. The valve 30 is held normally in a closed position. For so holding the valve 30, I have shown a means comprising a solenoid 39 having a magnetizing winding 40 and a magnetic circuit including an outer shell 42 and a core portion, one part 44 of which is annular in cross-section and fixed to shell 42 and extends centrally of winding 40 for part of its length. The other part of the core portion is movable with respect to the coil 40 and comprises an armature 46 fixed to the valve stem 32 so as to move therewith, stem 32 extending from valve 30 thru fixed part 44 and armature 46 lying on the other side of part 44 from the valve. Armature 46 is slidable in a central opening in the outer or upper end of casing 42 and is long enough to rest against or lie close to the part 44 when valve 30 is closed and still project thru or well into the shell so as to insure that the magnetic circuit of the shell 42 and core parts 44 and 46 shall be of low magnetic resistance. Solenoid 39 can therefore hold valve 30 shut against the opening means 34 without requiring a large holding current in winding 40. It will be understood, however, that winding 40 of solenoid 39 has enough turns and a low enough resistance in proportion to the voltage of the circuit in which it operates to pull armature 46 inward to close valve 30 whenever its circuit is closed.

The winding of the solenoid 39 is connected into a circuit comprising two wires 50 and 52 which will be understood as connected to a suitable source of voltage not shown, but indicated thus <V>. In the arrangement illustrated, wire 52 connects directly to the solenoid winding, but between wire 50 and the solenoid are connected two means for interrupting the circuit. One such means is a thermostat 54 illustrated in detail in Fig. 3. Thermostat 54 is of the thermometer type comprising a closed tube of non-conducting material, one end of which extends thru the wall 45 of the trap 20 at point 56 and projects into the trap so as to be subject to the temperature therein.

The tube of the thermostat 54 extends outwardly and upwardly from the outer surface of the wall of the trap 20 and is filled with a conducting liquid 58. Mercury is a filling liquid suitable for the purposes of the invention. The wire 50 is connected to a binding post 60 which extends thru the wall of the thermostat into the liquid 58 at a point well below the usual level of the surface of such liquid. Above the binding post 60 is a second binding post 62 which also extends thru the wall of thermostat 54 and into the liquid 58. Binding post 62 is at a level such that liquid 58 makes good contact therewith only when the lower and inner end of the tube of the thermostat is at a temperature above freezing, preferably above 40° F. Binding post 62 is connected by wire 64 to a mechanical make and break device enclosed in casing 66 and illustrated in detail in Figs. 5 and 6. Wire 64 connects to a binding post 68 which extends thru the casing 66 and on its inner end has a contact 70 adapted to make contact with a contact member 72 on a pivoted throw-over member 74 forming part of a snap-switch mechanism of known design within casing 66. Member 74 is connected to a binding post 76 by a wire 78 within the casing 66 and binding

post 76 is connected to the solenoid 39 by a wire 80, the circuit running from the end of wire 80 thru the solenoid winding 40 to the wire 52. The snap-switch mechanism within the casing 66 comprises further a spring 82 one end of which is pivoted to the inner facing of the casing and the other end of which is pivoted to the member 74. Spring 82 serves to hold the member 74 in either closed or open position until member 74 is moved past its neutral point by a level operated means. Such means comprises a float 84 within trap 20, the rod 86 of which is fixed to the shaft 88. Shaft 88 extends thru the wall of the trap and into the casing 66. Within casing 66 the shaft 88 has fixed thereto an operated member 90 having a pair of spaced fingers 92, 92 which embrace the tail piece 94 on the pivoted member 74 so that when shaft 88 is turned in one direction or the other by the float one of the fingers 92 contacts with tail piece 94 of the throw-over member 74 and moves such member to either make or break the circuit of solenoid 39. The position of float 84 is controlled by the water level in the trap 20.

It will be seen that I have provided two means for disabling the holding means for the valve 30. One such means is temperature controlled and the other is level controlled. If the water level in trap 20 rises to a certain point, the float 84 will operate the throw-over member 74 to break the circuit of solenoid 39 and thereby permit the spring 34 to open the valve 30. When sufficient water has been discharged thru valve 30, float 84 will close the circuit of solenoid 39 and thereby close the valve again. If, however, the water level is not high enough to raise the float 84 to permit valve 30 to open but the temperature close to the bottom of the trap for any reason should become so low as to approach the freezing point of the water in the trap, the mercury column 58 will contract to a point below the binding post 62 so as to break the circuit of the solenoid 39 and permit the valve 30 to open, thereby preventing freezing of the trap. It will be seen, however, that the thermostat 54 is not influenced by the temperature within trap 20 except at a level close to the bottom of the trap, so that there is positively no danger that the valve 30 will freeze shut even in very cold weather.

What I claim is:

1. A trap having a valve for controlling an outlet, means for applying a force tending to open said valve, means adapted to hold said valve closed, and both temperature operated means and water level operated means each adapted to disable said holding means to permit said valve to open.

2. A trap having a discharge valve, means for applying a force tending to open said valve, means adapted to hold said valve closed, and thermostatic means arranged to be affected solely by the temperature within said trap at a level close to that of said valve and adapted to disable said holding means to permit said valve to open.

3. A trap having a discharge valve, means for applying a force tending to open said valve, means adapted to hold said valve closed and including an electrical circuit having an electro-magnet connected therein, and thermostatic means adapted to break said circuit and having a part within said trap affected solely by the temperature at a level close to that of said valve.
